UNITED STATES PATENT OFFICE

WILLIAM ALLEN PUSEY, OF CHICAGO, ILLINOIS

COLLAR

Application filed October 24, 1927. Serial No. 228,186.

This invention pertains to collars, and more particularly to stiffening means for detachable soft collars.

Collars are generally divided into two classes, namely, stiff or starched, and semi-starched or soft collars. Many objections have been found for the universal use of stiff collars, such as lack of comfort in hot weather, laundering defects, etc., and because of these various objections, as well as the dictates of style, there has been developed a greater field of usefulness for the soft collar.

Soft collars are objectionable in some respects but principally because they more or less rapidly wilt, wrinkle, especially in front, and otherwise lose their shape.

It is therefore an object of this invention to provide a stiffening means which may be detachably applied to a soft collar to prevent wrinkling or distorting of the outer flap thereof.

Another object is to provide detachable stiffening means for soft collars which is positively maintained in a predetermined position.

A further object is to provide an inexpensive positive stiffening means for the flaps of soft collars which is detachable and fulfills all the requirements of service and manufacture.

A still further object is to provide a stiffening device for soft collars which will not distort the collar and may be applied to existing collars as well as to the new article of manufacture.

With these and various other objects in view, the invention consists of certain novel features of construction and operation as will be more fully described and particularly pointed out in the specification, drawings and claims appended hereto.

In the drawings, wherein like reference characters are used to designate like parts—

Figure 1 is a perspective of a soft collar,

showing in dotted lines the application of the invention thereto;

Figure 2 is a sectional elevation of the assembly shown in Figure 1, the same being taken substantially in the plane as indicated by the line 2—2 of Figure 1;

Figure 3 is an enlarged fragmentary detail elevation of the invention as applied to a soft collar, the collar being in opened out position to more clearly illustrate the application of the invention; and

Figure 4 is an enlarged elevation of the stiffening member.

The collar illustrated is of the well-known roll or turned-down type, having the conventional neckband 10 reenforced as at 11 and being provided with the usual front and back collar-button holes 12 and 13. The flap 14 or roll of the collar is shaped in any manner to conform to the dictates of style and may be reenforced along its edges by means of the facing 15, all in accordance with the usual practice.

The holder for the stiffening device may consist of an open ended sleeve 16 sewn or otherwise secured between the flap 14 and the neckband 10 adjacent but preferably spaced from the front of the collar 17 and on both sides of said front. This sleeve may be of any convenient length, such as approximately two inches, conforms substantially to the shape of the flap of the collar, and is secured along the bottom edge, as viewed in Figure 2, to the flap 14 adjacent the bottom thereof, sufficient material being provided to accommodate the stiffener in its operative position.

The holder adjacent the upper edge thereof, as viewed in Figure 2, is provided with a fold which is secured to the neckband 10 whereby when the collar is unrolled, i. e., when the flap 14 is revolved to coplanar position with respect to the neckband, the holder is extended permitting easy access of the stiffener. Although the sleeve has been thus described, it will be readily appreciated that any equiva-

lent means may be provided therefor, such as a number of spaced straps.

The stiffening device 18 may conveniently be made of celluloid though any other stiff and flexible material may be used which will not wilt or be otherwise distorted during wearing. This member is shaped substantially to conform to the shape of the collar, one edge thereof, preferably the bottom edge, being provided with a shoulder 19 adapted to engage with the rear edge of the sleeve for maintaining the stiffener in a predetermined position. This shoulder or off-set cut prevents the stiffener from slipping forward, distorting the collar, or showing, or being otherwise objectionable, and it will be seen that the engagement of the stiffener by the flap 14 keeps the shoulder or stop in operative position.

It will be seen with the construction illustrated and described that a very satisfactory arrangement is effected because the back edge of the cloth container is always at the same distance from the front lower edge of the collar, and the off-set cut in the stiffener will of course always be at a corresponding fixed point so that the stiffener will always fit properly in the holder and the off-set can drop behind its edge of the holder, always maintaining it in place, yet will be of such proportions as will effectively maintain the front of the collar in presentable condition.

It is to be understood that I do not wish to be limited by the exact embodiments of the invention illustrated, which are merely by way of illustration and not limitation, as other and various forms will of course occur to those skilled in the art.

I claim:

1. In a soft turn down collar, the combination of a neckband, an outer flap secured thereto, holders secured to the flap and neckband adjacent the front of said collar, said holders each having open ends, flexible stiffeners conforming substantially to the shape of the collar and being insertable through and into said holders, and means on the stiffeners adapted to engage a portion of the holders for maintaining said stiffeners in operative position.

2. In a soft turn down collar, the combination of a neckband, an outer flap secured thereto, holders secured to the flap and neckband adjacent the front of said collar, said holders each having open ends, flexible stiffeners conforming substantially to the shape of the collar and being insertable into one end of said holders, and means on the stiffeners adapted to engage a portion of the holders at the other end of said holders for maintaining said stiffeners in operative position.

3. In a soft turn down collar, the combination of a neckband, an outer flap secured thereto, tapered holders secured to the flap and neckband adjacent the front of said col-

lar, said holders each having open ends, flexible stiffeners conforming substantially to the shape of the collar and being insertable into one end of said holders, the taper of said holders limiting the position of said stiffeners, and an abutment on the stiffeners adapted to engage a portion of the holders at the other end of said holders for maintaining said stiffeners in operative position.

4. In a collar, the combination of a portion forming a neckband, a flap secured thereto, holders for stiffeners secured within said flap and neckband adjacent the front of said flap, said holders each being substantially tapering and each having open ends, the larger end of each of said holders being for the reception of the stiffener, each stiffener conforming substantially to the shape of the collar flap and being of substantially greater length than the length of said holder, each stiffener being provided with means for securing said stiffener within the flap.

5. In a collar, the combination of a portion forming a neckband, a flap secured thereto, holders for stiffeners secured within said flap and neckband adjacent the front of said flap, said holders each being substantially tapering and each having open ends, the larger end of each of said holders being for the reception of the stiffener, each stiffener conforming substantially to the shape of the collar flap and being of substantially greater length than the length of said holder, each stiffener being provided with a depending portion engageable with the lower edge portion of the holder and forming a stop to maintain said stiffener in operative position.

6. In a collar, the combination of a neckband, an outer turned down flap secured to said neckband, stiffener holders disposed between said neckband and flap adjacent the front of said collar and being substantially tapered and having permanently open ends, said holders being secured along one edge thereof to said flap and along the other edge thereof to said neckband, flexible stiffeners longer than said holders insertable into each of said holders, each of said stiffeners being tapered to correspond to said holders and of substantially the same configuration as said flap, a portion of said stiffeners being provided with a stop engageable with said holder for holding said stiffeners in operative position.

7. In a collar, the combination of a neckband, an outer turned down flap secured to said neckband, stiffener holders disposed between said neckband and flap adjacent the front of said collar and being substantially tapered and having permanently open ends, said holders each having a top portion turned down and secured to the top of said neckband and the bottom edge having a portion secured to said flap whereby when the flap is moved to a coplanar position with respect to said

neckband the holder is moved and extended, flexible stiffeners longer than said holders insertable into each of said holders, each of said stiffeners being tapered to correspond to said holders and of substantially the same configuration as said flap, a portion of said stiffeners being provided with a stop engageable with said holder, the stiffeners being of sufficient width whereby they are engaged by said flap when the collar is folded to operative position to thereby hold said stops in engagement with said holders for maintaining said stiffeners in operative position.

Signed at Chicago, Illinois, this 21st day
15 of October, 1927.

WILLIAM ALLEN PUSEY.
